Russell Benjamin Frisbey.

By Harry Q. Schroeder

Attorney

UNITED STATES PATENT OFFICE.

RUSSELL BENJAMIN FRISBEY, OF OAKLAND, CALIFORNIA, ASSIGNOR OF ONE-HALF
TO WILLIAM R. OAKLEY, OF OAKLAND, CALIFORNIA.

FURRING NAIL.

Application filed February 9, 1922. Serial No. 535,113.

To all whom it may concern:

Be it known that I, RUSSELL BENJAMIN FRISBEY, a citizen of the United States, residing at Oakland, in the county of Alameda and State of California, have invented certain new and useful Improvements in Furring Nails, of which the following is a specification.

My invention is an improved tack for hanging reinforcing wire fabric, commonly known as chicken wire, on the wooden supporting wall of plaster exterior wire, over which wire the plaster is placed.

Referring to the drawing forming a part of this specification:

Figure 1 is a vertical section of the wall of a plaster exterior building, with the wire reinforcement held in position by my tacks.

Figure 2 is a side view of my tack.

Figure 3 is a head end view of my tack. My tack comprises a shank 1 and a head 2 at one end of said shank, the other end of said shank being formed with a point 3. The head 2 has an annular groove 4 near the outer surface thereof, the head being rather deep so that the groove is spaced over an eighth of an inch from the inner surface of the head. The shank of the tack is driven into the wooden wall 5 until the inner sur-

face of the tack engages the outer surface of 30 said wall, the tacks being spaced about a foot apart vertically and horizontally. The wire fabric 6 is placed over said wooden wall and hooked in the grooves 4 of the tacks. The plaster 7 is then plastered on the 35 wall 5 over the wire fabric and the heads of the tacks as shown in Figure 1.

Having described my invention, I claim:

1. A tack including a shank pointed at one end, and a cylindrical head on the other end 40 of said shank, said head being provided with an annular groove near its outer end, the cross-section of the head in the plane of the groove being substantially larger than the cross-section of the shank. 45

2. A tack for supporting metal fabric upon a wall, comprising a pointed shank, and a cylindrical head of substantially greater radius than said shank, both bases of said cylindrical head being perpendicular to its axis, said head being provided with an annular groove spaced from its base so that when the tack is driven, the fabric will be spaced a predetermined 50 distance from said wall. 55

In testimony whereof I affix my signature.

RUSSELL BENJAMIN FRISBEY.
